H. PEMBERTON

TOY BALLOON

Filed Dec. 29, 1923

10 11 Inventor
12
Harold Pemberton.

By James E. Sproll

Attorney

UNITED STATES PATENT OFFICE.

HAROLD PEMBERTON, OF SEATTLE, WASHINGTON, ASSIGNOR, BY DIRECT AND MESNE ASSIGNMENTS, TO NATIONAL MANUFACTURING COMPANY, OF SEATTLE, WASHINGTON, A CORPORATION OF WASHINGTON.

TOY BALLOON.

Application filed December 29, 1923. Serial No. 683,283.

This invention is an improvement in toy balloons and the primary aim and fundamental object of the invention is the provision of a readily inflatable and deflatable 5 toy balloon secured in airtight relation upon the inner end of an inflating and deflating handle and enclosed by a protective casing of light material secured at the outer end of said balloon and at the inner end is designed 10 to snugly fit upon and be fixedly secured to the inner end of said handle, whereby the balloon when inflated is rendered substantially indestructible notwithstanding much rough usage and handling without injury 15 thereto.

The invention further resides in the provision of a toy balloon, of the type aforesaid, which may be fabricated in elongated or club-shaped formation, to form and constitute 20 an inflatable and deflatable club, adaptable for use as a game, wherein two or more players or opponents may participate without injury to the contestants, or which may be fabricated in any other desired shape 25 or formation for distribution, sale and use at carnivals, entertainments and celebrations of various kinds having the outer protective casing or covering thereof embellished with any desired or selected design or representation 30 apropos and suitable for the specific occasion.

The invention further resides in the provision of a toy balloon employing an exteriorly embellished protective casing and an 35 inflating and deflating handle, which is of comparatively simple, inexpensive and durable construction, that is positive and efficient in operation, and that will not readily get out of order.

With these and other ends in view the invention resides essentially in the novel construction, combination, adaptation and arrangement of parts, as will hereinafter be more fully described and succinctly defined 45 in the appended claims.

Referring now to the drawing wherein is illustrated the specific form of the invention, as at present preferred,

Figure 1 is a view in elevation of a toy 50 balloon fabricated in accordance with my invention, the same being illustrated in an inflated condition, and

Fig. 2 is a view in medial vertical section thereof.

In the drawings like reference numerals 55 designate like parts throughout the several views.

The numeral 3 designates a non-porous inflatable and deflatable bag of rubber, or other suitable non-porous material, having a constricted neck portion 4 adapted to fit upon and be secured in airtight relation upon the inner end of a tubular handle 5 fabricated from metal, wood or paper.

The non-porous bag 3 is adapted to be encased in a protective casing or covering 6 of silk or linen, or other suitable fabric, having a constricted neck portion 7 similar to that of the bag 3 and such neck portion 7 is adapted to fit over the neck portion 4 of the bag 3 and to extend beyond the outer end of the same to be fixedly secured upon the tubular handle 5.

To maintain the bag 3 in proper relation within the protective casing 6 and to insure 75 of the bag 3 properly filling out the casing 6 when the said bag is inflated I have found it advisable to secure the tip of the bag 3, at a point designated by the numeral 8 in Fig. 2, to the inner wall of the casing 6, 80 as by cementing the same thereto.

At the juncture of the casing 6 with the tubular handle 5 I have provided a sleeve 9 of any suitable material, adapted to protect and prevent tampering with the means 85 securing the said casing to the said handle, while, also serving to provide a more finished appearance for the device.

Mounted within the outer end of the tubular handle 5 is an air valve 10 adapted to 90 admit and retain the inflating air within the bag 3. The valve 10 may be of any well known type and in the present disclosure comprises a substantially annular casing 11 having an inlet aperture 12 adapted to be 95 normally closed by a rubber disc 13 when the bag 3 is inflated, and to prevent dislodgment of the disc 13 from an operative position a perforated metallic disc 14 is provided therefor adapted to seat within the inner end of the annular casing 11. The valve 10 may be fixedly secured within the tubular handle 5 in any desired manner, but, in the present disclosure I have illustrated the same as being secured therein by crimping the end 105 of the said handle thereon, such construction providing a very efficient and economical method for so doing.

The outer casing 6 may be exteriorly embellished with any suitable facial or other design or representation appropriate to the particular occasion for which the device is to be used.

In the present disclosure I have shown the device in the shape of a club which may be used as a game by two or more opponents with no danger of injury to the contestants, but, I desire to have it understood that the device may be constructed in many different shapes other than the one disclosed.

In the operation of the device the outer end of the tubular handle 5 is placed in the mouth and the bag 3 inflated whereupon the device is ready for use, and to deflate or collapse the device a blunt element is inserted within the inlet aperture 12 whereby the disc 13 is moved inwardly from the associated seat thereof to permit of the inflating air escaping from the bag 3.

In practice it has been found that by enclosing the rubber bag 3 in a fabric casing, as 6, that the device is rendered substantially indestructible and as such will withstand much hard usage and handling, while, with the casing omitted the life of the bag 3 is materially decreased and shortened.

While I have herein shown and described my invention with sufficient detail to enable those skilled in the art to understand the mode of construction and the principles involved, it is to be understood that there is no intentional limitation herein to the specific form and precise details of construction of the invention shown and described, except as expressly defined by the appended claims, and that various modifications of said construction may be resorted to without departing from the invention or the benefits derivable therefrom. I also desire to have it understood that certain features of the invention herein shown and described may be employed in other combinations than those herein shown.

Having thus fully described my invention, what I claim as new and desire to secure by Letters Patent of the United States is:—

1. In a toy balloon, in combination, an inflating and deflating handle, an inflatable and deflatable bag of elastic material having a constricted neck portion secured to the inner end of said handle, and a protective casing of inelastic material enclosing said bag and having a constricted neck portion secured to said inner end of said handle.

2. In a toy balloon, in combination, a tubular handle, an elongated inflatable and deflatable bag of elastic material having a constricted neck portion secured in airtight relation upon the inner end of said handle, an elongated protective casing of inelastic material enclosing said bag having a constricted neck portion fixedly secured upon said inner

end of said handle, and an inflating and deflating valve for said bag seated within said tubular handle.

3. In an inflatable and deflatable club, in combination, a club handle, an elongated inflatable and deflatable bag of elastic material having a constricted neck portion formed upon one end thereof secured in airtight relation upon the inner end of said club handle, an elongated protective casing of inelastic material enclosing said bag and secured thereto at the end opposite to the neck portion thereof having a constricted neck portion fixedly secured upon said inner end of said club handle, and an inflating and deflating valve for said bag to control the ingress of air thereto and the egress of the same therefrom.

4. In combination with a club-shaped toy balloon having a constricted neck, of an inflating and deflating handle secured within the constricted neck of said balloon, and a protective casing of inelastic material enclosing said balloon having a constricted neck adapted to fit snugly upon and be fixedly secured to said handle.

5. In combination with a toy balloon having a constricted neck, of a tubular handle snugly fitting and secured within the constricted neck of said balloon, an inflating and deflating valve for said balloon seated within said tubular handle, and an exteriorly embellished protective casing of inelastic material enclosing said balloon and secured thereto at the end opposite to the constricted neck thereof and having a constricted neck adapted to snugly fit upon and be fixedly secured to said tubular handle.

6. In a toy balloon, in combination, a tubular handle, an elongated non-porous inflatable bag having a constricted neck portion secured in airtight relation upon the inner end of said handle, an elongated fabric casing enclosing said bag having a constricted neck portion fixedly secured upon said inner end of said handle, a sleeve for said handle covering the juncture of the neck portion of said casing with said handle and an air valve for said inflatable bag secured within the outer end of said handle by crimping the end thereof upon said valve.

7. In a toy balloon, in combination, a tubular handle, an inflatable and deflatable bag of elastic material having a constricted neck portion engaging said tubular handle, a protective casing of inelastic material enclosing said bag and having a constricted neck portion attached to said tubular handle, and means to control the ingress of air to said bag and the egress of the same therefrom.

In testimony whereof I affix my signature.

HAROLD PEMBERTON.
